UNITED STATES PATENT OFFICE.

FRED M. HARRINGTON, OF WEEDSPORT, NEW YORK.

DESIGN FOR A DISPLAY-RACK.

SPECIFICATION forming part of Design No. 26,810, dated March 23, 1897.

Application filed January 27, 1897. Serial No. 616,426. Term of patent 7 years.

To all whom it may concern:

Be it known that I, FRED M. HARRINGTON, of Weedsport, county of Cayuga, State of New York, have invented and produced a new and original Design for a Display-Rack, of which the following, taken in connection with the accompanying drawing, is a full, clear, and exact specification.

In the drawing I show an isometrical view of my design for a display-rack, this one view being deemed sufficient to fully illustrate the same.

The leading feature of my design consists in a rectangular frame A, comprising top and bottom pieces b and vertical standards a, the said standards and cross-pieces having their

front faces rounded, and c are laterally-extending rods upon the standards a, that leave a space between the adjacent and converging ends.

Having described my invention, what I claim, and desire to secure by Design Letters Patent, is—

The design for a rack for displaying axes substantially as herein described and shown. 25

In witness whereof I have hereunto set my hand this 16th day of December, 1896.

FRED M. HARRINGTON.

In presence of—

MARY A. FRANKLIN,
HOWARD P. DENISON.
